MODULAR HOUSE

Emil A. Tessin II, Cuyahoga Falls, Ohio, assignor, by mesne assignments, to Alside Inc., a corporation of Ohio

Filed Oct. 22, 1962, Ser. No. 72,209

Term of patent 14 years

(Cl. D13—1)

FIG. 1

FIG. 2

FIG. 3

I claim:

The ornamental design for a modular house as shown.
